UNITED STATES PATENT OFFICE.

VICTORY LUCIAN SAWYER, OF NEW YORK, N. Y.

REMOVER FOR BOTTLE CLOSURES.

Application filed March 25, 1922. Serial No. 546,696.

To all whom it may concern:

Be it known that I, VICTORY LUCIAN SAWYER, a citizen of the United States of America, residing at New York, county of New York, and State of New York, have invented certain new and useful Improvements in Removers for Bottle Closures, of which the following is a specification.

This invention relates to that class of devices which are in use to some extent for the purpose of removing the paper closing disks which seal the mouths of milk bottles or the like, by means of a piercing member for the disk, although the invention can obviously be made of a material such as knife steel so that the remover could be used for removing those sheet metal closures which are frequently removably applied to receptacles, and are removed by forcing them off the receptacle. One of the objects of the present invention is to provide a practical, efficient and simple remover for bottle-closures, this preferably being done by making all parts thereof from one piece of sheet metal. Another object is to provide a special construction for the remover which lends itself more readily to the use for which the remover is particularly adapted, as in removing paper bottle-closures. These being among the objects of the present invention, the same consists of certain features of construction and combinations of parts to be hereinafter described, and then claimed with reference to the accompanying drawings illustrating one embodiment of the invention, in which:—

Fig. 1 is a side elevation of the device;

Fig. 2 a plan;

Fig. 3 is a section on line III—III, Fig. 1, transversely of the piercing-member;

Fig. 4 is a perspective view of the device; and

Fig. 5 is a sectional view, showing how the device is applied to a paper closure in order to remove it from the bottle.

The drawings show but one of the number of forms in which the present invention may be embodied, but the structure, shown in the form now preferred by me, consists of a sheet metal body-portion 10, which is preferably in the form of a circular disk having a diameter approximating that of the diameter of the mouths of the customary milk or cream bottles.

The body-portion 10 is provided with a piercing-member 11, which has a head with

two barbs 12, 12, so that said head is shaped like the head of an arrow, said head being connected with the body-portion 10 by a neck 13. The piercing-member is preferably formed by striking it up from the material of the body-portion 10 so that a hole 14 is formed in the body-portion of substantially the same shape as the piercing-member, and the said member is then bent away from the plane of the body-portion 10. From the cross section, Fig. 3, it will be seen that the barbs 12 are laterally bent relatively to the longitudinally axis thereof, or may be said to be twisted relatively to the plane of the piercing-member.

A suitable handle 15 is provided for manipulating the bottle-closure remover, and preferably such handle is of U-shape, approximately, and it is formed preferably by striking it up out of the material of the body-portion 10, so as to leave a U-shaped hole 16 corresponding substantially with the shape of the U-shaped handle.

In the preferred construction shown it will be seen that the piercing-member is formed by removing it from one-half of the body-portion 10, while the handle 15 is formed by removing it from the other half. As the U-shaped handle is struck up from within the disk-shaped body-portion in such proportions relative thereto as to leave parts of the body-portion, the original size and shape of the disk is maintained. Such construction will dispose the piercing-member 11 and the handle 15 in the same plane vertically, or transversely of the body-member, the piercing-member being connected with the body-member along the bending line at 17, while the handle is connected therewith along the bending line at 18. The arrangement shown is such that the arms of the handle span the neck 13 of the piercing-member, the legs of the handle being widely separated edgewise from the piercing member so as to leave considerable stock of the disk 10 around the piercing member to give it sufficient support and other obvious advantages.

When the device is made of sufficiently heavy sheet metal—although the metal is not necessarily so heavy that the device itself would not be light—a very simple, practical, efficient and ornate device for the purpose intended is provided.

From Fig. 5 it will be seen how the device is used for removing paper disks from milk or like bottles. It is only necessary to center

- the edge of the preferably circular body-portion, by means of the eye, with the paper disk, the operator taking hold of the handle and forcibly pressing the piercing-member into the disk. Whether the disk be firm or soft (due to saturation) the piercing-member will perforate the disk, and to connect the remover properly with the disk the remover is given a partial rotation, so that when the disk is lifted from the bottle the barbs 12 will bear upwardly on solid, and not perforated, parts of the disk. The lateral bending of the barbs tends to more surely remove the disk from the bottle if the disk be soft. As preferably the body-portion 10 corresponds substantially in size to the size of paper disk to be removed, a more perfect reclosing of the bottle is assured, as the said body will press substantially upon the whole area of the paper disk. The device is preferably made of sheet metal with the parts stamped or struck up, the whole device being nickel-plated or enameled, or suitably finished, in order to make it attractive, and it is of course obvious that if it

were made of blade or knife steel so as to adapt it for removing removable sheet metal tops it would be probably a more durable and expensive article.

It is obvious that the invention is susceptible to modification without departing from the scope of the claim.

What I claim as new is:

A remover for bottle-closures, comprising a sheet-metal disk-shaped body-portion, an arrow - headed closure - piercing member struck up in one direction from one-half of the body-portion, and a U-shaped handle struck up in opposite direction from within the said body portion out of the other half of said body-portion, the balance of the stock of the body-portion remaining in disk-form, the legs of said handle being spaced edgewise away from said piercing member and a substantial portion of the disk-shaped body-portion directly adjoining the piercing member, so that the handle distantly straddles and is in one plane with said piercing member.

V. LUCIAN SAWYER.
